(57) CLAIM

The ornamental design for a shoe, as shown and described.

DESCRIPTION

FIG. 1 is side view of a shoe showing our new design;
FIG. 2 is a rear-side perspective view thereof;
FIG. 3 is a rear view thereof;
FIG. 4 is a rear-opposite side perspective view thereof; and,
FIG. 5 is an opposite side view thereof.
The broken lines immediately adjacent to the shaded area define the bounds of the claimed design and form no part thereof. The broken lines depicting the remainder of the shoe show features that form no part of the claimed design.

1 Claim, 5 Drawing Sheets(56)
